UNITED STATES PATENT OFFICE.

FRANK B. GRANGER, OF NEW YORK, N. Y., ASSIGNOR TO HALL BORCHERT DRESS FORM COMPANY, OF NEW YORK, N. Y., A CORPORATION OF NEW JERSEY.

DRESS-FORM.

1,340,950.

Specification of Letters Patent.

Patented May 25, 1920.

Application filed May 15, 1919. Serial No. 297,184.

To all whom it may concern:

Be it known that I, FRANK B. GRANGER, a citizen of the United States, and a resident of New York, borough of Manhattan, in the county of New York and State of New York, have invented certain new and useful Improvements in Dress-Forms, of which the following is a specification.

This invention is an improvement in multiple-section adjustable dress forms, particularly of that type in which the form is built up of papier mâché, and when dry, cut into sections and the sections adjustably connected together. This adjustable connection in some forms or between certain sections of the form provides primarily for a swinging or pivotal movement, though it may also permit of a relative sliding movement in the same plane.

By my improved construction, I provide a simple, substantial, and inexpensive pivotal or hinge connection between adjacent sections of the form, which connection effectively prevents lateral or longitudinal relative sliding movement of the sections, permits free swinging movement, is practically concealed from view, lies within the confines of the thickness of the form wall so that there are no projecting parts, and is easily, quickly, and securely applied when assembling the form.

In the accompanying drawings:

Figure 1 is a front view of a dress form to which my invention may be applied.

Fig. 2 is a fragmentary face view on a larger scale showing the hinge connection between two sections at the waist line.

Fig. 3 is a section on the line 3—3 of Fig. 2.

Fig. 4 is a view similar to Fig. 2 but showing a slightly modified form.

Fig. 5 is a section on the line 5—5 of Fig. 2.

Fig. 6 is a perspective view of the hinge shown in Fig. 2, and

Fig. 7 is a perspective view of a hinge shown in Fig. 4.

In Fig. 1 I have shown a dress form built up of papier mâché to make a hollow shell which is then cut vertically, horizontally, and diagonally into the desired number of sections. Among these are a series of waist sections 10, and a series of hip or upper skirt sections 11. Above the waist sections 12 are a series of shoulder and neck sections 13

and sections 13 between these and the waist. So far as my present invention is concerned, I do not wish in any way to be limited to the number, character, or shape of these sections. In ordinary practice, the sections 10, 13, and 12 are adjustably connected together by slotted strips of spring steel forming slides and providing for the rigid clamping of the sections in the expanded or other adjusted relative positions. Similar slides may be provided between the several sections 11 although in my improved construction I do not employ such slides between the sections 10 and 11, but provide the improved hinge connection shown in Figs. 2 to 6 inclusive. In the form shown in Figs. 2, 3, and 5, I provide a pair of slots 14 in the opposed edges of the sections 10 and 11 and secure to the inner or outer face of each section a strip or plate of sheet metal 15 extending from one slot to the other and with its longitudinal edges substantially parallel to but spaced from the adjacent edges of the form sections. Each of these strips has a flange 16 at each end disposed substantially at right angles to the plane of the strip and disposed within the corresponding slot 14. Each flange is of a width not greater than the thickness of the wall of the section. Each flange 16 has an extension 17 in its own plane and projecting beyond the end of the wall between the planes of the opposite surfaces of the latter. The strip secured to one wall section is slightly shorter than that secured to the other, and the flange extensions 17 may thus overlap and lie in overlapping pairs. These are perforated and secured together by any suitable form of rivets or pivots 18. As a preferred means for securing the strips 15 to the wall of the sections, I provide rivets, the heads 19 of which may engage with the outer surfaces of the strips. The body of each rivet is in the form of a pair of prongs, which may separate as they are driven into the papier mâché wall and may curve or swage over in the material of the wall or along the opposite surface thereof, so as to prevent the withdrawal of the rivet. The strips 15 are comparatively thin and the rivet heads 19 comparatively flat so that they do not project to any objectionable extent from the surface of the wall. They may be pressed into the wall so as to lie substantially flush with the outer

surface of the latter due to the compressible character of the papier mâché. In practice each section has its outer surface covered with a loose woven fabric such as jersey and the edges of the fabric are folded around the edges of the section and pasted or glued to the curved surface. This fabric entirely conceals the hinge connection save for the very small portions visible through the narrow slot between sections.

I have shown such a fabric covering in section in Fig. 3.

In the form shown in Figs. 2, 3, and 5, the two pairs of hinge leaves 17 are connected together by the strip 15 so that the double hinge forms a single article easily applied. This is not essential as each strip 15 may if desired be cut in two so that the separate pairs of hinge leaves may be at different distances apart depending upon the size or curvature of the form. In Figs. 4 and 7 I have shown a slightly modified form in which the strips 15 are replaced by plates 15^a which are each perforated to receive a single rivet. To provide adequate and rigid anchorage for the hinge leaves, these plates are preferably somewhat wider than is necessary where the plate is in the form of a strip 15 as in Figs. 2 and 5.

The sections ordinarily curve as shown in Fig. 5, and the strips 15 are sufficiently flexible to permit the device to be attached irrespective of such curvature, the strip being bent to follow the wall. Such bending of the strip brings the flanges 16 out of parallelism but this is not important as the swinging movement of the sections 11 in respect to the sections 10 is ordinarily through a comparatively small angle and the material of the walls is sufficiently compressible and the material of the hinge connections sufficiently flexible to permit of the desired relative movement.

Although the slots 14 may be saw slots, or otherwise formed by the removal of material they may, due to the slight flexibility and compressibility of the material, be formed as cuts without the removal of the material.

Having thus described my invention what I claim as new and desire to secure by Letters Patent is:

1. In a dress form the combination of a pair of wall sections, each having a slot in the edge thereof, a pair of plates one secured to the surface of each of said wall sections adjacent to said edge and each having terminal flanges extending substantially at right

angles to the plane of the plate and disposed within said slots, said flanges having extensions projecting beyond the edges of said wall sections, and means for pivotally connecting said extensions in pairs.

2. In a dress form the combination of a pair of wall sections, a plate secured to each wall section and having a flange substantially at right angles to the plane thereof and each flange having an extension projecting beyond the edge of the wall section, and means for pivotally connecting said extensions.

3. In a dress form the combination of a pair of wall sections, each having one or more slots in the edge thereof, metal members within said slots and of a width not greater than the thickness of the wall sections, and having extensions projecting beyond the edges of said wall sections, each of said metal members having a portion substantially at right angles thereto and rigidly secured to the surface of the wall section adjacent to the slot, and means for pivotally connecting the extensions from one wall to those from another.

4. In a dress form the combination of a papier mâché shell subdivided into a plurality of sections, including waist sections and hip or upper skirt sections separated along a line encircling the waist, each of said waist sections having a slot therethrough extending upwardly from the lower edge thereof and each of said hip or upper skirt sections having a slot therethrough extending downwardly from the upper edge thereof, sheet metal plates secured to the surface of said sections and having flanges substantially at right angles to the planes of their respective plates and disposed within said slots, and means for pivotally connecting the flanges of the waist sections to the flanges of the hip or upper skirt sections.

5. In a dress form the combination of a hollow papier mâché shell, subdivided into sections, certain of said sections having slots therethrough extending inwardly from the dividing line between adjacent sections, sheet metal members disposed within said slots and projecting beyond the edges of their respective sections and each of a width not greater than the thickness of the section, means for securing each sheet metal member to its corresponding section, and means for pivotally connecting said sheet metal members together in pairs.

FRANK B. GRANGER
